MEANS FOR ALIGNING CALENDER ROLLS

Harrison R. Williams, New York, N. Y.

Application April 1, 1930, Serial No. 440,702

7 Claims. (Cl. 33—182)

This invention relates to the aligning of rolls to run in surface contact with each other and more particularly to the alignment of the rolls of a stack such, for example, as that of a calender for use in finishing a web of paper.

Where rolls are pressed together it is desirable to have them in close alignment for, if they are in skew relation with respect to each other there will not be a line of contact between them and 10 any article such as a web of material will not be subjected to uniform pressure throughout its width. Heretofore, no suitable means has been developed for determining whether such rolls are in alignment.

15 An important object of the present invention is to provide novel means for use in the alignment with respect to each other of rolls which are pressed together. Another object is to provide means for determining the degree of deviation 20 from such alignment.

The basic idea back of this invention is to provide for the establishment of what may be called a base or reference line or plane so that the distances therefrom of opposite ends of a 25 roll will determine whether or not the roll is properly aligned with respect to a standard direction. This base for reference may be established by using the bottom roll of a stack to establish a vertical base plane at a fixed distance 30 from the axis of such roll. The distances of opposite ends of an upper roll from such vertical base plane can then be measured and if they are different the upper roll is not in proper alignment 35 with reference to the lower roll.

35 Other objects and advantages will hereinafter appear.

In drawings forming part of the present specification:

Fig. 1 is a fragmentary end view of a stack 40 with one end of the frame removed and with one embodiment of the present invention applied thereto;

Fig. 2 is a diagrammatic view illustrating the 45 passage of a web of paper through a stack of rolls;

Fig. 3 is a fragmentary top plan view, in section, on a larger scale, taken along the line 3—3 of Fig. 1; and

Fig. 4 is a top plan view on a larger scale, of 50 the upper cross member of the aligning device, the upright being shown in cross section.

The objects of the invention can in general be attained by use of a device including an upright, a member adjustable along said upright 55 and designed to engage the lower or driving roll

of a stack at the side thereof, a cross member adjustable along said upright and designed to rest on a higher roll of the stack and thereby support the whole device with the lower adjustable member in engagement with the lower roll, 5 adjusting means carried by said upright in position to engage the side of such upper roll and serving to adjust said upright to vertical position, a micrometer gage adjacent said adjusting means and operable by engagement with 10 such upper roll, and means to vary the position of said micrometer gage with reference to the upright to obtain a zero reading.

After applying the aligning device at one end 15 of the stack and adjusting the same as above stated, the device may be shifted to the other end of the stack and the upright again adjusted to vertical position. The plus or minus reading 20 of the micrometer gage will then indicate in suitable linear units variations in alignment between the two ends of the roll being tested with 25 reference to the driving roll. The alignment of the upper roll may then be corrected in any suitable manner as by the use of shims between the body portions of the slidale end bearings of the upper roll and the edge portions of such bearings 25 which engage guides carried by the end frames of the stack.

Referring to Fig. 2 of the drawings, 1 indicates the lower or driving roll of a stack which 30 also includes a plurality of rolls 2, each supported by the next lower roll and driven frictionally therefrom; and 3 indicates a web of paper which is introduced beneath the upper roll 2 and passes back and forth around the rolls 2 until it reaches 35 the driving roll 1 where it is discharged from the stack.

As illustrated in Fig. 1, the driving roll 1 is provided at its ends with shaft sections 4 which are mounted in bearings of which the lower members 40 are parts of the end frames 5 of the stack, and the rolls 2 are provided at their ends with shaft sections 6 which are mounted in bearings 7 slid- 45 able on upright guides 8 carried on the adjacent faces of posts 9 forming parts of the end frames 5.

5. In order that rolls 2 may be aligned with reference to the driving roll 1 when found to be out of alignment therewith, the grooved edge portions of the bearings 7 which fit over the guides 8 are formed as separate members 10 so that adjustment of the rolls with reference to the guides 50 may be made by the insertion or removal of shims to vary the positions of the members 10 with reference to the corresponding bearings or bearing blocks 7. The members 10 may be attached 55

to the bearing blocks 7 in any suitable manner as by the use of screws 11 passing through the members 10 to one side of the grooves therein and threaded into the bearing blocks proper.

5 In machines in which articles, such as sheets or webs, are pressed by passing them between presser rolls, it is important to have line contact between adjacent rolls. Obviously such line contact will not be obtained if the rolls are in skew 10 relation or out of alignment with respect to each other. The present invention provides for testing the alignment of rollers and for measuring deviation from such alignment so that rolls which are out of alignment may be brought into alignment.

15 The illustrated embodiment of the invention includes a member or bar 12 which, when in use, is in an upright position and may therefore be referred to as an upright. Slidably mounted on 20 the bar 12 is a member 13 having an inner end which is designed to engage the lower roll 1 at its side and at the level of the axis of the roll. Preferably the roll engaging end of said member 13 is broad in the direction of the axis of the lower 25 roll so sidewise rocking of the testing device is prevented. Preferably the main body of the member 13 is provided at one side with a recess to receive the bar 12 and the bar is held in the recess by a plate 14 secured in position by suitable means such as screws 14a. Mounted in the outer end of said recess is a presser plate 15 held 30 in the recess by lugs 16 at the ends thereof and arranged to be pressed against the outer edge of the bar or upright 12 by means of a thumb screw 17 threaded through the outer end of the member 13. The reason for having the member 13 adjustable along the upright 12 will be brought out 35 hereinafter.

40 To support the alignment testing device, use is made of a cross member or bar 18 forming part thereof and arranged to rest on the upper side of the roll whose alignment with respect to the driving roll 1 is to be tested. The cross member 18 is also mounted on the bar or member 12 so that it can be adjusted therealong and to this 45 end the member 18 is provided with a suitable recess to receive the member or upright 12 which is held in the recess in any suitable manner as by means of a plate 19 and screws 20. To secure the cross member in adjusted position along the upright 12, provision may be made of suitable 50 means such as a presser plate 21 at the outer edge of the upright and held in the recess by lugs 22, and a thumb screw 23 threaded through 55 the outer end of the bar 18 for engagement with such plate.

60 In order to have a suitable base or base line to measure from at opposite ends of the stack, the upright 12 should be adjusted to the same position with reference to the lower roll 1 at both ends of the stack before the difference between the distances of the upright member is 65 determined. Preferably the upright 12 is adjusted to a vertical position by means of an adjusting screw or rod 24 designed to engage the roll whose alignment is to be tested. The screw 24 is perpendicular to the upright 12 and is threaded through a bracket 25 secured to the upright 12 at one side thereof. For convenience of operation the screw is provided at its outer end with a knurled head 26. In order to determine when the upright is in vertical position, use 70 may be made of any suitable means such as a surveyor's level 27 mounted on the cross member 18 by which the device is supported. Mounted on 75

the opposite side of the bar 12 from the bracket 25 is a bracket 28 (Fig. 3) in which is mounted a bar 29 parallel to the screw 24 and held in adjusted position in said bracket 28 by means of a thumb screw 30. Secured to the inner end of the 5 bar 29 is a micrometer gage 31 of a type to give both plus and minus readings and operated to give such readings by means of a plunger 32.

10 In installing the rolls of a calender stack, the bottom or driving roll 1 is installed in its fixed 10 bearings, the next roll 2 is installed, and after the two rolls have been run for a few minutes, say four or five minutes, the alignment of the upper 15 of the two rolls with reference to the lower is tested. In order to use the testing instrument of 15 the present invention, the cross member 18 is adjusted along the upright 12 until the distance 20 between its lower edge and the axis of the screw 24 is substantially the same as the radius of the roll 2 whose alignment is to be tested, and the 20 screw 23 is then tightened to maintain this adjustment. To facilitate the adjustment just referred to, the upright 12 may be provided with suitable graduations 33 which may be observed 25 through a sight opening 34 in the plate 19. The 25 member 13 for engagement with the lower roll should also be adjusted to a position such that the 30 distance from the axis of the screw to the medial horizontal plane through its contact end is substantially equal to the sum of the radii of the 30 two rolls.

35 After such adjustments have been made and the instrument located at one end of the stack with the cross member 18 resting on the upper of the two rolls, the member 13 against the lower 35 roll 1, and the screw 24 in engagement with the upper of the two rolls; the screw 24 is operated to bring the upright 12 to vertical position as indicated by bringing the bubble of the level to 40 central position determined by the positions of the ends of the bubble at equal distances on opposite sides of the zero graduation of a suitable 45 scale. The thumb screw 30 is then loosened and the bar 29 is adjusted longitudinally until the micrometer gage 31 has a zero reading. Then the instrument is shifted to the other end of the 50 stack and adjusted by means of the screw 24 until the upright 12 is vertical. The plus or minus reading of the micrometer gage 31 corresponding to any deviation of alignment will give sufficient information to enable the alignment to be 55 adjusted by use of shims or in any suitable manner.

Obviously another roll may be aligned with 60 reference to the upper roll shown in Fig. 1 or with respect to the lower roll after suitable adjustment of the members 13 and 18 along the upright. By continuing the operation in this way each roll installed may be aligned with respect to the rolls beneath the same.

65 While I have illustrated and described in detail one embodiment of my invention, it is to be understood that changes may be made therein. I do not, therefore, desire to limit myself to the specific construction illustrated but intend to 70 cover my invention broadly in whatever form its principles may be utilized.

I claim:

75 1. A device for testing the alignment of two rolls running in surface contact with each other, including an elongated part adapted to be positioned across such rolls in a plane substantially perpendicular to their axes, means to maintain said part at a constant distance from the axis of one of said rolls when placed at any position 75

therealong, micrometric means engageable with the other roll for adjusting said part to the same direction in any plane substantially perpendicular to the plane of said axes to determine gauging positions of said part, and indicating means settable to zero in a first gauging position and automatically operative in a second similar gauging position to indicate the difference in the distances from said part to the surface of said other roll in the two gauging positions.

2. A device for testing the alignment of two substantially parallel rolls arranged one above the other, including a straight bar, means carried by the bar and engageable with the lower roll for maintaining said bar at a fixed distance from the axis of the lower roll, means for resting upon the upper roll and supporting the bar therefrom, an adjusting screw carried by said bar and arranged to engage the circumference of the upper roll so that the bar may be brought by turning the screw to the desired position with the bar extending in a predetermined direction, and levelling means to indicate when said bar is in the desired position.

25 3. A device for testing the alignment of two substantially parallel rolls arranged one above the other, including a straight bar, means carried by the bar and engageable with the lower roll for maintaining said bar at a fixed distance from the axis of the lower roll, a screw carried by said bar and extending at right angles thereto to engage the upper roll and adjust the direction of said bar, a member extending from said bar to engage the top of the upper roll and support the testing device, said member being adjustable along said bar to make the distance from its roll engaging surface to the axis of the screw correspond with the radius of the upper roll, and means for measuring the distances from said bar to corresponding surface points of said upper roll when the bar is adjusted to corresponding positions at opposite ends of the rolls.

4. A device for testing the alignment of two substantially parallel rolls arranged one above the other, including a straight bar, a screw carried by said bar and extending at right angles thereto to engage the upper roll and adjust the direction of said bar, means carried by the bar and engageable with the lower roll for maintaining said bar at a fixed distance from the axis of the lower roll and including a roll engaging member adjustable along said bar to locate its roll engaging portion at a distance from the axis of the screw corresponding with the distance between the axes of the rolls, a member extending from said bar to engage the top of the upper roll and support the testing device, such supporting member being adjustable along said bar to make the distance from its roll engaging surface to the axis of the screw correspond with the radius of the upper roll, and means for measuring the distances from said bar to corresponding surface points of said upper roll when the bar is adjusted to corresponding positions at opposite ends of the rolls.

5. In a device for testing the alignment of two rolls, in combination, a supporting arm for resting on one of the rolls and adapted for adjustment to a level position, a member supported

therefrom and having a vertically extending face for engaging the periphery of one of the rolls in the horizontal plane of the axis thereof, a second roll-engaging member adjustable horizontally to engage the periphery of the second roll in the horizontal plane of the axis thereof to assist in securing and maintaining the level position of the supporting arm, a member depending from the supporting arm and carrying both of said roll engaging members, said device serving, when applied and adjusted at opposite ends of the rolls to determine a vertical base plane located at a predetermined distance from the axis of the first roll and in parallelism therewith, and an adjustable indicating means carried by the device, engageable with the periphery of the second roll in the horizontal plane of the axis thereof and settable to zero when the device has been applied and adjusted at one end of the rolls as described, said indicating means being automatically effective when the device is similarly applied and adjusted at the opposite end of the rolls to indicate the difference between the distances of the ends of the axis of the second roll from said base plane.

6. In a device for testing the alignment of two substantially cylindrical rolls, in combination, a member engageable with the periphery of one of the rolls in the horizontal plane of the axis thereof, a support for said member, a micrometric adjusting means carried upon the support and engageable with the periphery of the second roll in the horizontal plane of the axis thereof, said means being adjustable while in engagement with said roll to tilt the support and cause it to occupy a predetermined position relative to the vertical plane of the axis of the first roll, a micrometer indicator carried by the support and adjustable in parallelism with the roll engaging micrometric adjusting means, including a plunger engageable with the same element of the second roll engaged by the micrometric adjusting means, said indicator being adjustable to read zero when the device is applied and adjusted at one end of the rolls, and automatically operative when the device is applied and adjusted to the other end of the rolls to indicate the difference between the relations of the ends of the axis of the second roll to the vertical plane of the axis of the first roll.

7. In a device for gauging the position of relatively adjustable and fixed calender rolls, in combination, supporting means including spaced members having abutments constructed to be held against the side of the said rolls at one end thereof, means for setting said abutments in spaced positions in accordance with the distance from a vertical plane tangential to one of the rolls to a vertical plane tangential to the other roll, an indicating instrument associated with said supporting means having an element yieldably biased to engage one of said rolls, said device being movable to repeat the gauging operation at the opposite end of said rolls, and said indicating instrument having means when this second gauging operation has been effected to indicate automatically the extent of adjustment of the rolls required to bring the axes of said rolls into parallelism.

HARRISON R. WILLIAMS.
